United States Patent Office

Des. 226,732
Patented Apr. 17, 1973

226,732

CAMERA TRIPOD HEAD

Melville R. Pollard, Jr., Woodland Hills, Calif., assignor
to Cintel Corporation, Los Angeles, Calif.

Filed Apr. 12, 1971, Ser. No. 133,485

Term of patent 14 years

Int. Cl. D16—05

U.S. Cl. D61—1 G

Fig. 1

Fig. 2

Fig. 3

FIG. 1 is a left rear perspective view of a camera tripod head showing my new design;

FIG. 2 is a right side elevational view;

FIG. 3 is a top plan view;

FIG. 4 is a bottom plan view;

FIG. 5 is a front elevational view;

FIG. 6 is a rear elevational view; and

FIG. 7 is a left side elevational view showing the device in tilted position.

I claim:

The ornamental design for a camera tripod head, substantially as shown and described.
